(57) **CLAIM**

The ornamental design for a hook rail hook, as shown and described.

DESCRIPTION

FIG. 1 is a perspective view of a hook rail hook;

FIG. 2 is front elevation thereof;

FIG. 3 is a top view thereof;

FIG. 4 is a bottom view thereof;

FIG. 5 is one side view thereof; and,

FIG. 6 is another side view thereof.

The dash broken lines shown in the drawings are for purposes of illustrating portions of the hook rail that form no part of the claimed design. The rear portion of the hook is not visible during ordinary use and forms no part of the claimed design.
